(57) **CLAIM**

The ornamental design for a wastewater atomization nozzle, as shown and described.

DESCRIPTION

FIG. 1 shows a front-facing perspective view of a wastewater atomization nozzle showing my new design;

FIG. 2 shows a rear-facing perspective view thereof;

FIG. 3 shows a top plan view thereof;

FIG. 4 shows a bottom plan view thereof;

FIG. 5 shows a front elevation view thereof;

FIG. 6 shows a rear elevation view thereof;

FIG. 7 shows a left-side elevation view thereof;

FIG. 8 shows a right-side elevation view thereof; and,

FIG. 9 shows an environmental view of a wastewater atomization nozzle as part of a wastewater exhaust manifold for a wastewater evaporation system.

FIG. 1-8 broken lines represent portions of a wastewater atomization nozzle and FIG. 9 shows both environmental broken line and portions of a wastewater atomization nozzle. All broken lines form no part of the claimed design.
